W. C. H. SCOTT & W. ROBINS.
ROTARY VALVE INTERNAL COMBUSTION ENGINE.
APPLICATION FILED MAR. 15, 1916.

1,253,538.

Patented Jan. 15, 1918.

—FIG. 1.—

UNITED STATES PATENT OFFICE.

WILLIAM CHARLES HORACE SCOTT, OF LONDON, AND WILLIAM ROBINS, OF DARTFORD,
ENGLAND.

ROTARY-VALVE INTERNAL-COMBUSTION ENGINE.

1,253,538.

Specification of Letters Patent. Patented Jan. 15, 1918.

Application filed March 15, 1916. Serial No. 34,324.

To all whom it may concern:

Be it known that we, WILLIAM CHARLES HORACE SCOTT and WILLIAM ROBINS, both subjects of the King of Great Britain, and 5 residents of 46 Broomwood road, Battersea, London, England, and 41 Dartford road, Dartford, Kent, England, engineers, respectively, have invented new and useful Improvements in and Relating to Rotary- 10 Valve Internal-Combustion Engines, of which the following is a specification.

This invention relates to improvements in that type of internal combustion engine in which is employed a rotary distributing 15 valve having successive port spaces or cavities cut therein.

The main object of the present invention is to provide an engine of the above type so adapted as to counteract any harmful 20 action due to the high pressures and temperatures obtaining in the engine cylinders. To effect this a section is inserted into the 25 rotary valve cylinder in such a position as to close the port during compression and firing strokes. This section is so constructed that pressure on the portion exposed to the port area tends to close the outer edges against the walls of the valve cylinder container.

30 Further in conjunction with the above feature of the invention we employ spring rings, which do not rotate but remain stationary on the valve cylinder container wall, and provide against leakage between the 35 exhaust and induction ports or cavities in the rotary valve. We also make the exhaust passages in the rotary valve cylinder in a way to insure uniform heating and expansion of the metal, thereby enabling the 40 interior of the rotary valve to be used as a vaporizer.

We have illustrated our invention in the accompanying drawing which shows it applied to a four cylinder engine although it 45 is also applicable to engines having other numbers of cylinders.

Figure 1 is a plan view, the valve cylinder being in section and the rotary valve there- 50 in exposed to view.

Fig. 2 is a sectional elevation of an engine cylinder showing the position of a rotary valve when the piston is one quarter way down on the induction stroke, the induction port being barely full open.

55 Fig. 3 is a view of the same cylinder when

the piston is at the bottom of the induction stroke and just about to start upward on the compression stroke. The induction port has just closed.

Fig. 4 shows the position of the valve 60 when the explosion takes place. The self sealing section in the rotary valve is central with the port.

Fig. 5 is a view showing the position of the rotary valve when the piston is one 65 quarter of the way up on the exhaust stroke, the exhaust outlet having just reached the full open position.

1 are the cylinders of the engine; 2 the pistons; 3 the ports connecting the interior 70 of the cylinders with the rotary valve cylinder 4^a; 4 is the rotary valve or distributor within the cylinder 4^a; 5 is the spring section, let into the rotary valve 4, and forming a self sealing joint with the wall of the valve 75 cylinder 4^a when pressure is exerted on the center; 6 is a conduit in the valve 4 between the port 3 and the vaporizing chamber; 7 is the vaporizing chamber formed by the hollow center of the rotary valve 4 and supplied with fuel through the induction ports 8; 9 is the exhaust conduit formed on the 80 surface of the valve 4, the burnt gases pass along the conduits 9 under the spring rings 11 by undercut passages, communicating 85 with the exhaust outlet 10. 12 is the induction pipe through which fuel is supplied to the engine. 14 is a liner contained in the 90 valve cylinder 4^a and having in appropriate positions ports for the passage of the fuel 95 and the exhaust combustion products. 19 is a lubricating oil channel in the valve cylinder 4^a and the liner 14.

It will be observed that the ports 3 are adjacent to reduced portions of the rotary 95 valve 4 which are also pierced to allow access to the chamber 7 within the said valve. Fuel is drawn from the induction pipe 12 into the chamber 7 and there vaporized by the heat of the engine. As the valve 4 is 100 rotated by means which it has not been thought necessary to specify, the supply and exhaust conduits 6 and 9 are brought in their proper turn opposite the port 3. The section 5 which serves to close the port 3 during 105 and after the explosion consists of a curved plate let into the circumference of the rotary valve in such a way that the central portion has behind it an empty space and the edges have an inclined or beveled 110

bearing against its seat. Under the force of the explosion, which takes place when the section 5 is opposite the port 3 (as in Fig. 4), the plate slightly flattens and expands 5 its edges against the interior of the liner 14 so as to spread and make a tight joint. The rings 11 which are like piston rings are situated in annular grooves in the valve and serve to separate each portion thereof from 10 its neighbor. The passage 9, formed in the metal of the valve to lead the products of combustion from the cylinders to the exhaust ports 10 extend sidewise beneath the rings 11 as appears from the right hand 15 end of Fig. 1. 15 are pins for retaining the sections 5 in position when the valve is withdrawn for cleaning or other purposes. The spring rings can be pulled out with the valve and reinserted through one end of the liner. 20 Normally however they rest stationary within the latter while the valve rotates.

What we claim and desire to secure by Letters Patent of the United States is:—

1. In combination, a valve cylinder and a 25 valve therein, the said valve being provided with a spring section consisting of a curved plate having a reduced central portion with inclined edges, the said section being adapted under external pressure to flatten and 30 spread its edges against the cylinder wall to form a tight joint.
2. A rotary valve for internal combus-

tion engines comprising a hollow chamber acting as a passage and vaporizer for the fuel, a conduit leading therefrom and adapted to meet the cylinder port at the time of induction, a surface conduit in the valve adapted to meet the cylinder port at the time of exhaust and a spring section in the valve adapted to spread thereby closing more 40 tightly the cylinder port during and after explosion.

3. A rotary valve for internal combustion engines comprising a hollow chamber acting as a passage and vaporizer for the fuel, a 45 plurality of conduits leading therefrom and adapted to meet in turn the ports of a corresponding number of cylinders at the time of induction, surface conduits in the valve adapted to meet the cylinder ports at the 50 time of exhaust, spring sections in the valve adapted to spread thereby closing more tightly the cylinder ports during and after explosion and piston rings separating each portion of the rotary valve from the neighboring portion.

In testimony whereof we have signed our names to this specification in the presence of two subscribing witnesses.

WILLIAM CHARLES HORACE SCOTT.
WILLIAM ROBINS.
